FOOT OPERATED SHOE BRUSHING DEVICE

Frederick E. Hummel, Chicago, Ill.

Application February 7, 1948, Serial No. 6,923

2 Claims. (Cl. 15—37)

1
This invention has to do with a device for brushing shoes while on the wearer's feet and has for its primary object to provide a device of that character which can be installed in any convenient place and which avoids the necessity of the user soiling his hands or even stooping over.

A further object is to provide a shoe-brushing device of the above indicated type which is sturdy enough to withstand hard usage and yet so designed that it can be manufactured economically, so as to be saleable at an attractive price.

Still another object is to provide a shoe-brushing device which operates quickly and efficiently and enables the users thereof to brush their shoes frequently, with little exertion thus maintaining a neat appearance at all times.

Referring to the drawings which accompany this specification:

Fig. 1 is an elevational view of a shoe-brushing device, illustrating, by way of example, one of the preferred embodiments of the invention;

Fig. 2 is a view of the same device, partly in elevation and partly in vertical section, and taken at right angles to Fig. 1; and

Figs. 3 and 4 are sectional views looking upwardly at the line 3—3 of Fig. 1, illustrating alternate positions of various moving parts of the device.

The shoe-brushing device illustrated comprises a relatively massive base 10, which may conveniently be of cast iron, preferably having sufficient weight to hold the device steady; unless the base is to be anchored to the floor, in which case it may be of lighter weight. Said base 10 has a central hub portion 11 with a vertical bore 12 and an annular recess 13 in which is seated the lower end of a coil spring 14.

A post 15, consisting of a round rod or shaft, fits slidably in the bore 12 and is reciprocable therein as well as rotatable. Said post 15 has an external helical groove 16 of rather long pitch, which is engaged by a pin or screw 17 threaded into the hub 11. Obviously, as the post 15 is moved up and down, it is at the same time rotated, first one way and then the other, by virtue of the helical groove 16 and the pin 17. Spring 14 urges post 15 upwardly toward the position in which it is shown in Fig. 2, and the lower end of helical groove 16 is stopped short of the lower

extremity of the post so as to limit the extent of upward movement.

A cap 18, which may be a casting of any suitable metal, is fixedly secured to the top of post 15, so that it rotates with the post; and a platform or foot-rest 20 is pivotally secured to and carried by either cap 18 or post 15. In either event, the platform is supported by and moves up and down with the post, but does not rotate therewith. Platform 20 is of a suitable area, horizontally, to provide a satisfactory foot rest, and it is flanged downwardly along its lengthwise edges 20a, both to afford rigidity and for other reasons which presently will be seen. Said platform also 15 is flanged upwardly at 20b to form a toe-stop, so that the user's shoe will be properly positioned, as depicted in Fig. 2.

Mounted just below platform 20 is a slide plate 22 having a pair of elongate slots 23, and an oblong slot 24, in addition to a pair of arms 25 which extend through a pair of lengthwise extending slots in one of the flanges 20a, as sufficiently illustrated in Figs. 1 and 3.

Slide plate 22 is supported from platform 20 by means of a pair of shouldered screws 26, which pass through the slots 23 and are threaded into the platform. The oblong slot 24 provides clearance around post 15 to enable the slide plate to move lengthwise relatively to the post.

There are three shoe brushes 28, 29 and 30. Brushes 28 and 29 are positioned to brush opposite sides of a shoe, and brush 30 is positioned to brush the top surface of the toe portion of the shoe. The bristles are long enough and resilient enough so that the three brushes, conjointly, reach substantially all the exposed surfaces of the shoe. Brush 30 is fixedly secured to and carried by brush 29. Brush 28 is fixedly secured to the upright portions of arms 25, which are integral with slide plate 22; and brush 29 is fixedly secured to a pair of angle irons 32, the horizontal legs 32a of which pass through and are slidably supported in a pair of slots in one of the flanges 20a. Said horizontal legs are provided with lengthwise slots 33, through which pass a pair of shouldered screws 34. These latter are threaded into the slide plate 22 and have heads which serve to secure the arms 33 in place while at the same time enable the angle irons 33 to move, together with brushes 29 and 30, in the

direction widthwise of the user's shoes. A pair of coil springs 36 are each secured at one end to the horizontal leg of one of the two angle irons 32 while the other ends of said springs are anchored to the slide plate 22. It will be apparent that springs 36 constantly urge the brush 29 toward the user's foot and, therefore, toward brush 28; and that said springs serve to press brushes 28 and 29 against the shoe being brushed, while at the same time being yieldable enough to enable the user to push his foot into the space between said brushes without undue effort.

Another coil spring 37 is connected at one end to slide plate 22 and at the other end to platform 20; and it will be evident that the latter 15 spring constantly urges the slide plate rearwardly.

The brushes function by reciprocating horizontally, lengthwise of the shoe, and they all move together, relatively to the platform 20, 20 forwardly and rearwardly in successive strokes.

It will now be explained how the reciprocation of the brushes is accomplished as a result of pressing down with the foot on platform 20. The downward pressure causes post 15 to move downwardly, together with all the parts supported thereon, against the opposition of spring 14; and, as previously stated, this causes post 15 and cap 19 to rotate. In this instance the groove 16 comprises a little more than two complete convolutions. Consequently, a full downward movement causes post 15 and cap 19 to make slightly more than two revolutions during each downward stroke, and again during each upward stroke. When the operator has pressed the platform and post all the way down, as shown in Fig. 1, he releases the pressure, thus allowing spring 14 to restore the aforesaid parts to their up positions, as depicted in Fig. 2; and he may repeat the operation as many times as desired.

Referring more particularly to Figs. 3 and 4, it will be seen that cap 19 has four radially extending arms 19a; and it will further be seen that there is an arm 40 pivotally connected at 41 to the slide 22, and that there is a stop pin 42 secured to the slide plate against which said arm 40 is urged by a coil spring 43.

During each downward stroke cap 19 rotates clockwise, as viewed in Figs. 3 and 4—making two complete revolutions per downward stroke; and it makes an equal number of revolutions during each upward stroke. Manifestly, as cap 19 rotates clockwise from the position in which it is shown in Fig. 4, the radial arm 19a, shown bearing against arm 40 will push said arm 40 against stop pin 42 and, consequently, cause the slide plate 22 to move forwardly, as illustrated in Fig. 3, to a sufficient extent to allow the active radial arm to escape arm 40. The forward movement of the slide plate effects a like movement of the brushes, and as soon as the momentarily active arm has rotated to the point of escape, the slide plate is quickly returned to the starting point by spring 37, carrying the brushes with it. The next arm 19a thereupon engages arm 40 and thus brings about another forward stroke of the slide plate, which in turn, is followed by another rearward stroke, as before; and so on until the slide plate and brushes have been reciprocated eight times. This is followed by two counterclockwise revolutions of cap 19, incidentally to upward movement of the post; but during this period the slide plate and brushes are not reciprocated, and the radial arms 19a freely escape the arm 40 because the latter is not restrained against clock-

wise rotation, except for the slight restraint effected by spring 43. It will be seen that what I have illustrated and described is a one-way reciprocating means. Any mechanism which would cause reciprocation of the brushes during the upward strokes of the post would entail the need for such a forceful restoring spring as to require an excessive downward pressure, except perhaps for people of considerable weight. Obviously, a cam drive which would reciprocate the brushes during the upward as well as the downward strokes would be even simpler than the one-way drive I have shown and described, and I do not wish to exclude from the scope of my invention any shoe-brushing devices involving my inventive concept but designed to reciprocate the brushes during both the upward and downward strokes or during only the upward strokes. I have not shown any such alternative arrangements because I consider it sufficient to disclose the superior embodiment of the invention which I have already disclosed.

There are, of course, many possible modifications and alternatives within the purview of my invention, and, accordingly, I do not wish to be limited save as indicated by the terms of the appended claims.

Having described my invention, what I claim as new and wish to secure by Letters Patent is:

30 1. A shoe-brushing device, comprising: a base, a round vertical post journaled in said base for both rotation about its vertical axis and lengthwise vertical reciprocation, means for limiting the vertical movement of said post, a spring continuously urging said post toward the upper limit of its travel, said post having an external helical groove, means carried by said base and engaging said groove whereby said post is rotated in one direction in response to each downward movement thereof, and rotated in the opposite direction in response to each upward movement thereof, a foot-rest platform mounted upon and carried by said post and rotatable relatively thereto, a slide supported by and mounted immediately below said platform and reciprocable in a horizontal path relatively to said platform, a spring biasing said slide toward one end of its path, a pivoted arm carried by said slide, stop means for limiting rotation of said pivoted arm in one direction a plurality of arms carried by and extending radially from the upper end of said post, said radial arms being arranged to successively engage said pivoted arm and thereby to force said slide toward the other end of its path when said post is rotated in one direction, thereby causing said slide to reciprocate along its horizontal path, said pivoted arm being yieldable in the other direction of rotation so that when said post rotates in the return direction said radial arms are ineffective upon said slide, and a plurality of brushes carried by said slide and disposed in engaging relation to a shoe superimposed upon said platform.

65 2. In a shoe-brushing device, a base, a round vertical post journaled in said base for both rotary and lengthwise reciprocation, said post extending upwardly from said base and having an external helical groove, a pin affixed to said base and engaging said groove and effective thereby to cause rotary reciprocation of said post in response to lengthwise reciprocation thereof, a spring biasing said post upwardly from said base, a foot-rest platform pivotally mounted on the top of said post and supported thereby, a slide 70 plate disposed immediately below said platform

and supported thereby, said slide plate being reciprocable lengthwise of said platform along a horizontal path, a spring biasing said slide plate toward one end of said path, a member carried by said post and rotatable therewith and having a plurality of radially extending circumferentially spaced arms, a pivoted arm carried by said slide plate and disposed in the path of said radial arms, stop means for said pivoted arm, a spring normally holding said pivoted arm against said stop means, said radial arms being effective, when rotating in a direction to press said pivoted arm against said stop means, to move said slide plate toward the other end of said path, said pivoted arm being arranged to allow said radial arms to escape engagement therewith when said slide plate has reached a predetermined limit of travel along said path, so that the slide plate is freed to return along said path to a position wherein it is engageable by a succeeding radial arm, and a plurality of brushes carried by said slide plate and

so disposed as to be engageable with a shoe superimposed upon said platform.
